US00D843281S

(12) **United States Design Patent** (10) **Patent No.:** **US D843,281 S**
(45) **Date of Patent:** **** Mar. 19, 2019**

(54) **VEHICLE HOOD**

(71) Applicant: **Oshkosh Corporation**, Oshkosh, WI (US)

(72) Inventors: **Jesse Gander**, Oshkosh, WI (US); **Christopher Yakes**, Oshkosh, WI (US)

(73) Assignee: **Oshkosh Corporation**, Oshkosh, WI (US)

(**) Term: **15 Years**

(21) Appl. No.: **29/621,958**

(22) Filed: **Oct. 12, 2017**

Related U.S. Application Data

(63) Continuation of application No. 15/599,174, filed on May 18, 2017, which is a continuation of application No. 14/724,279, filed on May 28, 2015, now Pat. No. 9,656,640, application No. 29/621,958, which is a continuation of application No. 14/612,100, filed on Feb. 2, 2015, now Pat. No. 9,829,282, which is a continuation of application No. 13/841,686, filed on Mar. 15, 2013, now Pat. No. 9,045,014, which is a continuation of application No. 13/629,009, filed on Sep. 27, 2012, now Pat. No. 8,943,946.

(57) **CLAIM**

We claim the ornamental design for a vehicle hood, as shown and described.

DESCRIPTION

FIG. 1 is a front perspective view of the claimed design; FIG. 2 is a front view of the claimed design; FIG. 3 is a rear view of the claimed design; FIG. 4 is a left side view of the claimed design; FIG. 5 is a right side view of the claimed design; FIG. 6 is a top view of the claimed design; FIG. 7 is a bottom view of the claimed design; FIG. 8 is a second front perspective view of the claimed design; and, FIG. 9 is a detailed front perspective view of the claimed design.

Evenly-spaced broken lines depict unclaimed environmental subject matter. Dot-dash broken lines depict unclaimed boundaries of the claimed design.

1 Claim, 9 Drawing Sheets
